UNITED STATES PATENT OFFICE.

CUTHBERT C. CATHCART, OF KALAMAZOO, MICHIGAN, ASSIGNOR TO KALAMAZOO STOVE COMPANY, OF KALAMAZOO, MICHIGAN.

GRATE FOR FURNACES OR BOILERS.

Application filed April 25, 1928. Serial No. 272,657.

The main objects of this invention are: First, to provide an improved grate for furnaces and boilers which effectively supports the grates for rocking movement and 5 also for tilting adjustment so that the grate may be raked or cleared.

Second, to provide a grate structure in which the grate bars may be quickly and easily placed in position or removed as occasion 10 may require.

Objects pertaining to details and economies of my invention will definitely appear from the description to follow. The invention is defined in the claims.

15 A structure embodying the features of my invention is clearly illustrated in the accompanying drawing forming a part of this application, in which:

Fig. 1 is a front elevation of a hot air 20 furnace embodying the features of my invention, the hot air casing being indicated by dotted lines.

Fig. 2 is a fragmentary horizontal section on line 2—2 of Fig. 1.

25 Fig. 3 is a fragmentary view partially in vertical section on a line corresponding to line 3—3 of Figs. 2 and 4.

Fig. 4 is a detail view partially in section on line 4—4 of Figs. 2 and 3.

30 Referring to the drawing, 1 represents the body of a hot air furnace and 2 the casing thereof. The ashpit 3 is provided with supporting bearings 4 for the rear ends of the grate bars 5 which are mounted in these 35 bearings for rocking and longitudinal tilting movement. The front ends of the grate bars are rockingly mounted on the supporting bar 6 which has grooved annular bearings 7 for the front journals 8 of the grate 40 bars.

The support 6 is provided with downwardly projecting fixed arms 9 which are pivoted to the lower ends of the hangers 10. The hangers are supported by the pivots 11 45 on the ashpit top wall 12, the wall having housings 13 projecting upwardly therefrom and into which the upper ends of the hangers project as shown in Fig. 3. The support is provided with a crank-like handpiece 14 at 50 one end.

The side wall 15 of the ashpit has a guide 16 for one end of the bar or support 6 while the wall 17 has a slot 18 through which the support 6 projects so that when the support 55 is rotated on its axis it is raised and lowered

in the guides, its lowered position being indicated by dotted lines in Fig. 4. When in this position the grate bars are supported in a forwardly inclined position and may be raked or cleared.

60 The hangers 10 are angled or bent so that when the support is in its elevated or erected position shown in Fig. 3 the pivots 19 for the arms 9 swing past the vertical center or axis of the support so that the supporting 65 bar is automatically locked in its erected position. The hanger links and the arms in effect constitute a locking toggle which, however, is broken by the rotative movement 70 of the support, swinging the pivots 19 past the center of the support.

The grate bars are provided with arms 20 connected by the links 21 so that they may be simultaneously rocked.

75 The shaker lever 22 is pivoted at 23 on the outside of the casing 2 and is connected by the link 24 to one of the arms 20 of the grate bars so that they are simultaneously shaken or rocked in their bearings. The 80 grate bars are disposed at an angle to the face 25 of the furnace and the face of the casing is provided with a recess 26 in which the shaker lever is mounted, thus providing for a direct connection for the shaker lever to the grate bars.

85 Further, by arranging the grate bars at an angle to the ashpit opening, they are all readily accessible for removal or replacing.

I have illustrated and described my improvements in an embodiment which I have 90 found very practical. I have not attempted to illustrate or describe certain other embodiments which I contemplate as it is believed that this disclosure will enable those skilled in the art to embody or adapt my 95 improvements as may be desired.

Having thus described my invention what I claim as new and desire to secure by Letters Patent is:

1. In a structure of the class described, the 100 combination of a plurality of grate bars mounted at their rear ends for rocking and longitudinal tilting movement and having depending arms at their front ends, pivoted hangers adjacent the front ends of said bars, 105 a grate bar support provided with a plurality of annularly grooved bearing members for the front ends of said grate bars and having arms pivotally mounted on said hangers, vertical guides for the ends of said 110

grate bar support, said grate bar support having a handpiece at one end whereby it may be rotated and thereby raised and lowered in said guides, a link pivotally connected to said arms, and a shaker lever operatively connected to one of said grate bar arms.

2. In a structure of the class described, the combination of a plurality of grate bars 10 mounted at their rear ends for longitudinal tilting movement, pivoted hangers adjacent the front ends of said bars, a grate bar support provided with a plurality of annularly grooved bearing members for the front ends 15 of said grate bars and having arms pivotally mounted on said hangers, and vertical guides for the ends of said grate bar support, said grate bar support having a handpiece at one end whereby it may be rotated 20 and thereby raised and lowered in said guides.

3. In a structure of the class described, the combination of a plurality of grate bars mounted at their rear ends for rocking and 25 longitudinal tilting movement and having depending arms at their front ends, pivoted hangers adjacent the front ends of said bars, a support for the front ends of said grate bars and having arms pivotally mounted on 30 said hangers, vertical guides for the ends of said grate bar support, said grate bar support having a handpiece at one end whereby it may be rotated and thereby raised and lowered in said guides, a link pivotally connected to 35 said arms, and a shaker lever operatively connected to one of said grate bar arms.

4. In a structure of the class described, the combination of a plurality of grate bars 40 mounted at their rear ends for longitudinal tilting movement, pivoted hangers adjacent the front ends of said bars, a support for the front ends of said grate bars and having arms pivotally mounted on said hangers, 45 and vertical guides for the ends of said grate bar support, said grate bar support having a handpiece at one end whereby it may be rotated and thereby raised and lowered in said guides.

50 5. In a structure of the class described, the combination of grate bars mounted at their rear ends for rocking and for longitudinal tilting movement, pivoted hangers adjacent the front ends of said bars, a sup-

port on which the front ends of said bars 55 are rockingly mounted having arms pivotally connected to said hangers, said support being provided with guides whereby the support is raised and lowered in its guides by a rotative movement of the support, and 60 means for rocking said grate bars.

6. In a structure of the class described, the combination of grate bars mounted at their rear ends for longitudinal tilting movement, pivoted hangers adjacent the front 65 ends of said bars, and a support on which the front ends of said bars are mounted having arms pivotally connected to said hangers, said support being provided with guides whereby the support is raised and lowered 70 in its guides by a rotative movement of the support.

7. In a structure of the class described, the combination of grate bars mounted for longitudinal tilting movement, pivoted hangers 75 adjacent the front ends of said grate bars, a support for the front ends of said grate bars having arms pivotally mounted on said hangers, and guides for said support.

8. In a structure of the class described, the combination of grate bars mounted for longitudinal tilting movement, pivoted angled hangers, a support for the front ends of said grate bars having arms pivotally mounted on said hangers, the angles of said hangers 85 being adapted to receive said support when it is in erected position, thereby permitting the support to swing past the plane passing through the hanger pivots and the pivots connecting said arms to said hangers and 90 providing a locking toggle, and guides for said support.

9. In a structure of the class described, the combination of grate bars mounted for longitudinal tilting movement, pivoted angled hangers, and a support for the front ends of said grate bars having arms pivotally mounted on said hangers, the angles of said hangers being adapted to receive said support when it is in erected position, thereby permitting the support to swing past the plane passing through the hanger pivots and the pivots connecting said arms to said hangers and providing a locking toggle.

In witness whereof I have hereunto set my 105 hand.

CUTHBERT C. CATHCART.
